UNITED STATES PATENT OFFICE.

ARTHUR H. GIBSON, OF EASTON, PENNSYLVANIA, ASSIGNOR TO
INGERSOLL-RAND COMPANY, OF NEW YORK, N. Y., A CORPO-
RATION OF NEW JERSEY.

COAL-CUTTING MACHINE.

No. 818,619.

Specification of Letters Patent.

Patented April 24, 1906.

Application filed November 15, 1905. Serial No. 287,401.

To all whom it may concern:

Be it known that I, ARTHUR H. GIBSON, a subject of the King of Great Britain, and a resident of Easton, in the county of Northampton and State of Pennsylvania, have invented a new and useful Improvement in Coal-Cutting Machines, of which the following is a specification.

My invention relates to improvements in coal-cutting machines, and more particularly to certain improvements in the construction, form, and arrangement of the several parts of an air-presser-driven coal-cutting machine whereby the operation thereof is facilitated.

The object of this invention is to provide an automatic governor for coal-cutting machines which are operated by reciprocating or pulsating columns of air whereby the stroke of the piston when the cutter is not striking coal may be reduced.

In the accompanying drawings, Figure 1 represents the coal-cutting machine in connection with an electrically-driven air-presser for operating the same, the parts being shown in side elevation, partially broken away. Fig. 2 is an enlarged longitudinal central section through the machine, the piston being shown at the limit of its forward movement when the cutter is striking coal. Fig. 3 is a top plan view of the machine, the valve-chest being removed and a part of the cylinder being broken away to more clearly show the arrangement of the ports therein. Figs. 4 and 5 are end and longitudinal sectional views, on an enlarged scale, of the governor-plunger; and Fig. 6 is an enlarged detail section showing the governor check-valve.

The cylinder of the coal-cutting machine is denoted by 1, which cylinder is surmounted by a valve-chest 2. This valve-chest 2 is divided into front and rear chambers 3 and 4 by a manually-operated valve 5, having a through-port 6, whereby the two chambers may be brought into open communication with each other for throwing the machine out of operation. Flexible air-tubes 7 and 8 lead from the front and rear chambers 3 and 4 of the valve-chest 2 to the front and rear ends 9 and 10 of the cylinder 11 of the air-presser, which air-presser in the present instance is shown as being driven from the electric motor 12, the presser and its driving-motor being mounted on a suitable portable

truck 13. The coal-cutting machine is mounted on suitable traction-wheels 14 and is provided with the usual handle 15 for guiding it into position for use. The cutter-piston is denoted by 16 and its rod by 17.

Divided main front ports 18 lead from the front chamber 3 in the valve-chest to points 55 a short distance to the rear of the front end of the cylinder-chamber. An auxiliary front port 19 leads from the front chamber 3 of the valve-chest to the extreme front end of the cylinder-chamber through a one-way valve 65 20, arranged to open by pressure from the front chamber 3 of the valve-chest and to close against pressure from the cylinder-chamber in front of the piston 16.

A rear port 21 leads from the rear chamber 70 4 in the valve-chest to the cylinder-chamber a short distance from its rear end. An auxiliary port 22 leads from the port 21 to a point close to the rear end of the cylinder-chamber through a one-way valve 23, which will open 75 by pressure from the rear chamber 4 of the valve-chest and will close against pressure from the cylinder-chamber back of the piston 16.

The governor for reducing the stroke of the 80 piston 16 when the cutter is not striking coal is constructed and arranged as follows: The governor-plunger is denoted by 24, and it is fitted to slide in a cylindrical chamber 25 in the valve-chest 2. The mouths of the divided main front ports 18, which open into the front chamber 3, are also located in this cylindrical chamber 25 in position to be opened and closed by the sliding plunger 24. The plunger is guided in its forward and backward sliding movements by providing a stationary pin 26, carried by the valve-chest, and side elongated slots 27 in the plunger. The plunger is held normally at the limit of its forward movement by providing the plunger 95 with a longitudinal recess 28, in which a spring 29 is located. A plate 30 is held within the recess at the back end of the spring 29 by set-screws 31, carried by the plunger. A port 32 leads from the front end of the work-cylinder chamber to the forward end of the plunger-chamber 25 in front of the plunger 24.

A governor check-valve 33 is located in the port 32, which check-valve is arranged to 105 open by pressure from within the work-cyl-

inder in front of the piston and is arranged to close by back pressure from the plunger-chamber. This governor check-valve 33 has a small passage 34 therein, which serves as a leak, so that the pressure from the plunger-cylinder may slowly leak past the check-valve 33 back into the work-cylinder.

The operation of the governor is as follows: When the cutter is striking coal, the piston 16 reaches the point shown in Fig. 2 at the limit of its forward movement. When the cutter does not strike coal, the piston 16 will continue its forward movement, thus overrunning the mouths of the ports 18 in the cylinder-chamber. The further forward movement of this piston 16 will force the air in front of the same through the port 32 and past the governor-valve 33 into the chamber in front of the governor-plunger 24. This will force the governor-piston rearwardly against the tension of its spring 29 and cause the plunger to close the mouths of the divided main front ports 18 in the front chamber 3 of the valve-chest, thus cutting off the divided main front ports 18 at this point. When the column of air passes from the presser through the pipe 7 into the front chamber 3 for causing the return stroke of the piston, some of the same will pass down through the auxiliary front port 19 and past the valve 20 into the cylinder-chamber in front of the piston 16. The air which passes in this manner will be only sufficient to move the piston rearwardly a part stroke. If the cutter on the next forward stroke of the work-piston strikes coal, the air will slowly leak past the governor check-valve 33, and thus permit the spring to slowly force the governor-plunger forwardly, and thus open the divided main ports 18, and thereby feed the full capacity of air to the front of the piston 16 to cause it to resume its full working stroke. If, however, the cutter on the said next forward stroke fails to strike coal, the conditions will remain the same as before, the overrunning of the piston 16 of the divided main ports 18 serving to keep sufficient pressure in the port 32 and the front of the plunger-chamber to keep the plunger at the limit of its rearward movement against the tension of its spring.

What I claim is—

1. In an air-presser-driven coal-cutting machine, a work-cylinder, its piston, air-passages leading to the front and rear of the cylinder and a governor controlled by the movement of the piston for reducing the stroke of the said piston.

2. In an air-presser-driven coal-cutting machine, a work-cylinder, its piston, air-passages leading to the front and rear of the cylinder and a governor controlled by the movement of the piston beyond its normal forward limit for automatically reducing the supply of air to the front of the piston for reducing its stroke.

3. In an air-presser-driven coal-cutting machine, a work-cylinder, its piston, a rear air-port, a main front port, an auxiliary front port and a governor controlled by the movement of the piston for cutting off the supply of air through the main front port for reducing the stroke of the piston. 70

4. In an air-presser-driven coal-cutting machine, a work-cylinder, its piston, a rear air-port, a main front port, an auxiliary front port and a governor controlled by the movement of the piston beyond its normal forward limit for cutting off the main front port to reduce the stroke of the piston. 75

5. In an air-presser-driven coal-cutting machine, a work-cylinder, its piston, a rear port, a main front port, an auxiliary front port, and a governor for controlling the stroke of the piston comprising a plunger, its cylinder, a spring for yieldingly holding the plunger in position to leave the main front port open and a port leading from the front of the work-cylinder to the front of the plunger whereby the excessive forward movement of the piston will cause the air to force the plunger back into position to close the main front port and thus reduce the supply of air to the front of the piston. 80 85 90

6. In an air-presser-driven coal-cutting machine, a work-cylinder, its piston, a rear port, a main front port, an auxiliary front port, a governor for controlling the stroke of the piston comprising a plunger, its cylinder, a spring for yieldingly holding the plunger in position to leave the main front port open, a port leading from the front of the work-cylinder to the front of the plunger whereby the excessive forward movement of the piston will cause the air to force the plunger back into position to close the main front port and thus reduce the supply of air to the front of the piston, and a governor-valve for partially closing the plunger-controlling port for temporarily retaining air-pressure on the plunger irrespective of the position of the piston. 95 100 105 110

7. In an air-presser-driven coal-cutting machine, a work-cylinder, its piston, a valve-chest divided into front and rear chambers, a rear port leading from the rear chamber to the rear of the work-piston, a main front port leading from the front valve-chest chamber to the front of the piston at a distance from the end of the cylinder, an auxiliary front port leading from the front valve-chest chamber to the front of the piston adjacent to the end of the cylinder, a spring-actuated governor-plunger located in the valve-chest normally in position to leave the main front port open and a port leading from the front of the said plunger to the front end of the work-cylinder whereby the governor-plunger is moved rearwardly to close the main front port when the work-piston overruns the limit of its normal forward movement. 115 120 125

8. In an air-presser-driven coal-cutting 130

5 machine, a work-cylinder, its piston, a valve-chest divided into front and rear chambers, a rear port leading from the rear chamber to the rear of the work-piston, a main front port leading from the front valve-chest chamber to the front of the piston at a distance from the end of the cylinder, an auxiliary front port leading from the front valve-chest chamber to the front of the piston adjacent to the end of the cylinder, a spring-actuated 10 governor-plunger located in the valve-chest normally in position to leave the main front port open, a port leading from the front of the said plunger to the front end of the work-cylinder whereby the governor-plunger is 15

26 moved rearwardly to close the main front port when the work-piston overruns the limit of its normal forward movement, and a governor-valve arranged to partially close the port leading from the plunger to the cylinder for temporarily retaining air-pressure on the plunger.

25 In testimony that I claim the foregoing as my invention I have signed my name, in presence of two witnesses, this 13th day of November, 1905.

Corrections in Letters Patent No. 818,619.

It is hereby certified that in Letters Patent No. 818,619, granted April 24, 1906, upon the application of Arthur H. Gibson, of Easton, Pennsylvania, for an improvement in "Coal-Cutting Machines," errors occur requiring correction, as follows: In the specification and claims the word "presser" wherever it occurs should read *pressor* and the word "pressers" should read *pressors*; and that the said Letters Patent should be read with these corrections therein that the same may conform to the record of the case in the Patent Office.

Signed and sealed this 15th day of May, A. D., 1906.

Commissioner of Patents.

5 machine, a work-cylinder, its piston, a valve-chest divided into front and rear chambers, a rear port leading from the rear chamber to the rear of the work-piston, a main front port leading from the front valve-chest chamber to the front of the piston at a distance from the end of the cylinder, an auxiliary front port leading from the front valve-chest chamber to the front of the piston adjacent to the end of the cylinder, a spring-actuated 10 governor-plunger located in the valve-chest normally in position to leave the main front port open, a port leading from the front of the said plunger to the front end of the work-cylinder whereby the governor-plunger is 15

26 moved rearwardly to close the main front port when the work-piston overruns the limit of its normal forward movement, and a governor-valve arranged to partially close the port leading from the plunger to the cylinder for temporarily retaining air-pressure on the plunger.

25 In testimony that I claim the foregoing as my invention I have signed my name, in presence of two witnesses, this 13th day of November, 1905.
